UNITED STATES PATENT OFFICE.

HARRY A. TAYLOR, OF NEW YORK, N. Y.

DESIGN FOR A GLOVE.

55,339.

Specification for Design.

Patented May 25, 1920.

Application filed September 13, 1919. Serial No. 323,664. Term of patent 3½ years.

To all whom it may concern:

Be it known that I, HARRY A. TAYLOR, a citizen of the United States, residing at the borough of Manhattan, city, county, and State of New York, have invented a new, original, and ornamental Design for Gloves, of which the following is a specification, reference being had to the accompanying drawings, forming part hereof.

Figure 1 is a perspective view of the back of the glove in position upon the hand;

Fig. 2 is a view the same as Fig. 1 except that the pointed wrist end of the glove is turned back upon the glove;

Fig. 3 is a plan view of the back of the wrist end of the glove;

Fig. 4 is a plan view of the front of the wrist end of the glove.

I claim:

The ornamental design for a glove, substantially as shown.

HARRY A. TAYLOR.
